DENTAL FONT

Hyman Freedman, New York, N. Y.

Application December 15, 1948, Serial No. 65,329

7 Claims. (Cl. 4—263)

1

This invention relates to improvements in dental fonts and has for one of its objects to provide an improved construction of font wherein a quantity of medicament, such as mouth wash, may be automatically supplied in solution with each cup of water drawn from the font.

Another object is to support a medicament container in communication with a water reservoir and connected auxiliary chamber in such manner that the flow of liquid through said reservoir and chamber will cause a pressure to be created in said container which, upon cessation of said flow, will have the effect of discharging therefrom a limited quantity of medicament into said auxiliary chamber to form a solution with the water therein which will be subsequently discharged therefrom when said flow is again turned on.

Another object is to mount the auxiliary chamber so that the same may be adjusted from a normal to a draining position to enable the solution therein to be discharged without the necessity of turning on the flow of water through the system.

A further object is to increase the temperature of the solution to be discharged from the font by providing said reservoir or said auxiliary chamber, or both, with a heating element.

The above and other objects will appear more clearly from the following detailed description when taken in connection with the accompanying drawings which illustrate a preferred embodiment of the inventive idea.

In the drawings:

Fig. 1 is a fragmentary side elevation, partly in section, of a dental font constructed in accordance with the invention;

Fig. 2 is a similar view in front elevation, the dot and dash lines indicating the drainage position of the auxiliary chamber;

Fig. 3 is a section on the line 3—3 of Fig. 1; and

Fig. 4 is a section on the line 4—4 of Fig. 1.

The invention is shown in its application to a dental font of well known construction which comprises a hollow pedestal 5 (Fig. 2) constituting a drain and provided with a laterally extending drain pipe 6 which supports the usual cuspidor 7. The upper end of the pedestal 5 terminates in a housing 8 in which is mounted the usual main control valve 9 having the various positions indicated on the housing. When using a saliva ejector, the valve is turned to the "suction" position and when desiring to flush the

cuspidor 7, the valve is turned to the "flush" position to direct the water from the source of supply into the branch pipe 10 and thence into the downwardly inclined extension 11 thereof which leads into said cuspidor. The third operative or "water" position of the valve 9 directs the flow into the branch pipe 12 which extends upwardly through the housing. The construction thus far described is well known and needs no further amplification. From the pipe 12, water flows into the bottom of the circular reservoir 13 which is kept filled from said source. Said reservoir is connected to the housing 8 by a suitable coupling 14 and has a central drainage opening 15 in the bottom thereof through which excess liquid may flow into the hollow pedestal 5.

The top wall of the reservoir 13 is depressed and its bottom is inclined as indicated at 16 so as to guide the cup holder 17 and its cup 18 to a central position where said holder abuts against a shoulder 19 to thus maintain the cup in proper position to receive liquid in a manner to appear in the course of the description. Within 20 in the water chamber formed by the reservoir and adjacent the inlet of the pipe 12, there is mounted a partition 20 shown in dotted lines in Fig. 3 which causes the water entering said chamber to circulate counterclockwise as viewed in said figure before exiting into the small outlet pipe 21 and thence downwardly into the lower end of a normally vertically arranged auxiliary tubular chamber 22. The upper end of said chamber has extending laterally therefrom the restricted outlet pipe 23 the outer end of which is disposed directly over the cup 18 when the chamber 22 is in normal position. The pipe 23 may have a valve 24 as is customary but the use of said valve in the present construction is optional. The connection of the lower end of the chamber 22 with the pipe 21 provides a pivotal mounting for said chamber whereby the same may be swung to the downwardly inclined position indicated in dotted lines in Fig. 2 where- 25 in the outer end of the pipe 23 is located directly over the cuspidor 7. This adjustment of the chamber 22 and pipe 23 is provided for the purpose of draining the contents of said chamber for use by a patient when he desires to cleanse 30 a denture before handing it to the dentist for inspection, after which the chamber and pipe 23 may be swung back to their normal positions.

Means are provided for raising the temperature 35 of the liquid in the reservoir and auxiliary

chamber so as to reduce the possibility of pain to a patient caused by a cold liquid when the content of the cup 18 is used as a mouth rinse. For heating the reservoir, a heat conducting ring 25 is supported in the bottom of said reservoir adjacent the drain opening 15 in thermal contact with said reservoir. Embedded in said ring is the heating element which may be a coil 26 by means of which the bottom and walls of the reservoir are heated only sufficiently to raise the temperature of the water contained therein to a degree to remove the chill therefrom. Some of the heat from the coil 26 will also pass upwardly through the drain 15 and thus warm the contents of the cup 18 through the opening 17 in the bottom of the holder 17.

The chamber 22 may also be provided with a heating element 27 therein to maintain liquid in said chamber at the desired temperature. A terminal block 28 is mounted on housing 8 and is provided with contacts 29 adapted to be engaged by wipers 30 connected to the heating element 27 when the chamber 22 is in normal position. Said contacts 29 are also connected, by conductors 31, to the terminals of the heating element or coil 26, and a conductor 32 (Fig. 4) is joined to a source of current supply through a step-down transformer (not shown).

The construction as thus far described enables the flow of a clear and temperate supply of water from the source through the reservoir into the outlet pipe 21 and thence into the auxiliary chamber 22 and through the outlet pipe 23 when the valve 9 is turned to the "water" position. Because of this flow, a pressure is created in the reservoir and pipe 21, and due to the restricted nature of the pipe 23 the water will flow therethrough with the desired velocity.

The invention further provides means for supplying a limited quantity of medicament to the auxiliary chamber 22 to form a mouth wash solution therein, the medicament being of greater specific gravity than water. For this purpose, there is provided a medicament container 33 which is mounted upon the top wall of the reservoir 13 and which is of arcuate formation in cross section so as to conform to the contour of the wall upon which it rests. The top of the container has a closure 34 grooved to frictionally receive the pipe 23 when the latter is in normal position. By swinging the pipe slightly to one side, the closure 34, which may be threaded into the top of the container, is removable when refilling the container with a medicament. The top of said container also has mounted therein an air vent valve 35 of conventional construction which admits air into the container when the valve is open and closes under influence of pressure within the container, as will presently appear. The lower end of the container 33 is provided with a restricted outlet 36 in direct communication with the upper end of the pipe 21 and, consequently, with the chamber.

In operation, upon opening the valve 9 to the "water" position, pressure will be created in the reservoir 13 and communicated to the pipe 21 where it will enter the outlet 36 of the container 33, and this pressure will build up in the air space at the top of said container by closing the air vent 35. The flow of water through the reservoir and auxiliary chamber will then discharge a solution of medicament and water mixed in said chamber by a previous operation, and if the flow of water is allowed to continue after discharge of the solution, clear and cold water will

then flow through the pipe 23 for drinking purposes. Upon closure of the main valve, pressure in the reservoir and pipe 21 is reduced to zero and the pressure in the top of the container 33 now acts to discharge a small quantity of medicament into the chamber 22 through the pipe 21 to mix with the water therein. As said pressure becomes effective, the air vent valve 35 will open by reason of the tendency to create a vacuum therein as the liquid level lowers and atmosphere is then admitted to the container. When the weight of the liquid in the container equalizes with that of the column of the solution now in the auxiliary chamber, the system becomes stable and is ready for the next opening of the valve 9.

What is claimed is:

1. In a dental font, a water reservoir having connection to a source of supply, an auxiliary chamber in communication with said reservoir and having an outlet, a medicament container connected to said auxiliary chamber and to said reservoir for receiving pressure therefrom when said supply is turned on, valve means in said container controlling the flow of medicament therefrom into said auxiliary chamber when said water supply is shut off, and means to heat the contents of said reservoir and chamber.

2. In a dental font, a water reservoir having connection to a source of supply, an auxiliary chamber in communication with said reservoir and having an outlet, means to mount said auxiliary chamber for movement to a draining position, a medicament container connected to said auxiliary chamber and to said reservoir for receiving pressure therefrom when said supply is turned on, and valve means in said container controlling the flow of medicament therefrom into said auxiliary chamber when said water supply is shut off.

3. In a dental font, a water reservoir having connection to a source of supply, an auxiliary chamber in communication with said reservoir and having an outlet, a medicament container having a restricted outlet connecting the same to said reservoir and chamber for receiving pressure from said source of supply through said reservoir when said supply is turned on and for feeding a limited supply of medicament to said auxiliary chamber under the influence of said pressure when said supply is shut off, valve means in said container for controlling said pressure to thereby limit the amount of medicament flowing from said container, and a heating element mounted in said auxiliary chamber.

4. In a dental font, a water reservoir having connection to a source of supply, an auxiliary chamber in communication with said reservoir and having an outlet, a medicament container having a restricted outlet connecting the same to said reservoir and chamber for receiving pressure from said source of supply through said reservoir when said supply is turned on and for feeding a limited supply of medicament to said auxiliary chamber under the influence of said pressure when said supply is shut off, valve means in said container for controlling said pressure to thereby limit the amount of medicament flowing from said container, a heating element mounted in said auxiliary chamber, and means to mount the latter chamber for movement to drainage position.

5. In a dental font, a water reservoir having connection to a source of supply, an elongated vertically disposed auxiliary chamber mounted exteriorly of said reservoir and extending above the same, a medicament container supported on

said reservoir and having a valve controlled air vent, an outlet pipe connecting said reservoir with the lower end of said auxiliary chamber and also having a restricted connection with the lower end of said container, and an outlet pipe for said auxiliary chamber extending from the upper end thereof.

6. In a dental font, a water reservoir having a recessed upper surface provided with a drainage opening, an elongated vertically disposed auxiliary chamber mounted exteriorly of said reservoir and extending above the same, a medicament container supported on said reservoir and having a valve controlled air vent, an outlet pipe connecting said reservoir with the lower end of said chamber and also having a restricted connection with the lower end of said container, and an outlet pipe for said auxiliary chamber extending laterally therefrom and over said container and having its outlet end disposed above the drainage opening in said reservoir.

7. In a dental font, a water reservoir having an inlet pipe connected thereto, an elongated auxiliary chamber mounted exteriorly of said reservoir, a medicament container supported on said reservoir and having a valve controlled air vent, an outlet pipe connecting said reservoir with one

end of said auxiliary chamber and also having a restricted connection with the lower end of said container, a partition in said reservoir between said inlet and outlet pipes for producing a circuitous flow of water from the former to the latter pipe, means to heat the water as it flows through said reservoir and an outlet pipe for said auxiliary chamber extending from its other end and over said reservoir.
